Patented Nov. 25, 1919.

2 SHEETS—SHEET 2.

UNITED STATES PATENT OFFICE.

FREDRICK ANDREW SCHATZ, OF PHILADELPHIA, PENNSYLVANIA.

WEATHER-STRIP.

1,322,732.

Specification of Letters Patent. Patented Nov. 25, 1919.

Application filed February 20, 1919. Serial No. 278,311.

To all whom it may concern:

Be it known that I, FREDRICK ANDREW SCHATZ, a citizen of the United States, residing at Philadelphia, in the county of Philadelphia and State of Pennsylvania, have invented certain new and useful Improvements in Weather-Strips, of which the following is a specification.

One object of my invention is to provide an improved weather-strip which will be particularly well adapted for use in connection with windows for keeping the sash tight so as to prevent air from passing between the sash and the frame, and also for preventing rattling of the sash.

Another object is to so construct my improved weather-strip that it will have a part resiliently pressing upon the sash when the sash is closed and will also include parts which will serve to move said resiliently pressed part out of engagement with the sash during the initial opening movement of the sash; thereby removing all friction between the resilient pressed part and the sash during the continued opening movement of the sash.

A further object is to make my improved weather-strip of a strong and durable construction and so that the parts thereof can be easily and quickly manufactured and assembled.

These objects, and other advantageous ends which will be described hereinafter, I attain in the following manner, reference being had to the accompanying drawings in which—

Figure 1 is a front elevation of my invention illustrating its relation to a window sash when the sash is in its closed position,

Fig. 2 is a view of similar nature to that shown in Fig. 1 illustrating the parts as they appear when the sash has been slightly raised to release friction of the weather-strip upon the sash,

Fig. 3 is a transverse section taken on the line 3—3 of Fig. 6, showing my invention attached to a window frame and in frictional engagement with the sash,

Fig. 4 is a transverse section taken on the line 4—4 of Fig. 1,

Fig. 5 is a transverse section taken on the line 5—5 of Fig. 2,

Fig. 6 is a sectional elevation of my im-

proved weather-strip and taken on the line 6—6 of Fig. 4, and

Fig. 7 is a fragmentary perspective view of certain of the parts of my invention.

Referring to the drawings, 8 represents a window frame having a sash 9 slidable vertically therein.

My invention includes a channel-shape casing 10 which is preferably made of pressed sheet metal; one side portion 11 being of greater width than the other side portion 12 so as to provide an extension 13 adapted to receive screws 14 for attachment to the frame 8. The top and bottom ends 15 and 16 of the casing 10 are closed and extend at right angles to the side portions 11 and 12 and their connecting portion 17.

An elongated channel-shape shoe 18 has its side portions 19 and 20 adapted to slide between the side portions 11 and 12 of the casing 10. The portion 21 of the shoe 18 between the side portions 19 and 20 extends the full length of the shoe as clearly shown in Fig. 6 and together with the closed ends 22 and 23 of the shoe forms a closure for the interior of the casing 10. The top 22 and bottom 23 of the shoe 18 extend at right angles to the portions 19, 20 and 21 and are adapted to slidably engage the inner surfaces of the top 15 and bottom 16 of the casing 10.

A bracket 24 has a leg portion 25 which extends through a slot 26 in the side portion 20 of the shoe 18 and is soldered or otherwise secured to the inner surface of the portion 21. The bracket 24 has a portion 27 which extends parallel with and directly adjacent the side portion 12 of the casing 10.

The portion 27 of the bracket 24 has a transversely extending slot 28 therein and through this slot and also through holes 29 in the portions 11 and 12 of the casing 10 is adapted to extend a screw 30. The end 31 of the screw 30 is designed to enter the frame 8 and assist in securing the weather-strip to the frame as clearly shown in Fig. 4. The screw 30 has an enlarged portion 32 which provides a shoulder 33 which is adapted to abut the outer surface of the side portion 12 of the casing 10; it being

noted that the holes 28 in said side portions 11 and 12 are of less diameter than the width of the slot 28. Thus the shoulder 33

will abut the outer side surface of the portion 12 and limit the inward movement of the screw 30. The side portions 19 and 20 of the shoe 18 have notches 34 which straddle the screw 30 and other screws 35 which also extend through the casing 10 and serve as additional securing means for said casing to the frame 8.

By the above construction it will be understood that the shoe 18 is free to slide into and out of the casing 10. I interpose resilient means within the casing 10 and shoe 18, said resilient means serving to move the shoe out of the casing. This resilient means is made in a number of units according to the length of the casing and shoe. In the accompanying drawings and as shown in Fig. 6 the resilient means consists of two units 36 and 37 and since these units consist of identical parts it is only necessary to describe one of the units and it will be understood that the other unit includes similar elements serving in the same capacity. Each unit includes a bowed spring 38 having lugs 39 therein. The end portion 40 of the bowed spring 38 is adapted to engage the inner surface of the portion 21 of the shoe 18. The intermediate portion 41 is secured to a strip 42 by a bolt 43, said bolt also passing through the portion 17 of the casing 10. The opposite end portions of the strip 43 having lugs 43^a thereon which are respectively in alignment with the lugs 40. The lugs 40 and 43^a provide positioning means for two coiled cushion springs 44. By this arrangement the springs 38 and 44 serve to move the part 21 of the shoe 18 into frictional engagement with the sash 9.

The part of the screw 30 between the shoulder 33 and the head 45 forms a pivot support for a latch 46. The latch 46 has two arms 47 and 48 and a cam portion 49 as clearly shown in Figs. 1 and 2. An actuating finger 50 is secured to the sash 9 and when the sash is in its closed position as shown in Fig. 1 the finger 50 is positioned between flanges 51 and 52 on the arms 47 and 48 respectively. Also as shown in Fig. 1, the low part of the cam 49 is in engagement with a lip 53 which projects forward from the bracket 24. When the sash 9 is raised the finger 50 engages the flange 51 of the arm 47 and turns the latch 46 on its pivot and at the same time causes the high portion of the cam 49 to engage the lip 53 of the bracket 24 and cause the shoe 18 to be moved out of engagement with the sash 9; this movement taking place against the action of the springs 38 and 44. After this initial opening movement of the sash, the sash can be freely moved the remainder of the distance necessary to completely open it. When the sash is again lowered the finger 50 will engage the flange 52 of the arm 48 and thereby swing the latch on its pivot

and move the high portion of the cam 49 away from the lip 53 permitting the springs 38 and 44 to again move the shoe 18 into frictional engagement with the sash.

It will be noted that when the shoe 18 is in engagement with the sash that it will prevent rattling of the sash and at the same time it will form a seal to prevent air from passing between it and the sash.

By making the resilient pressing means in units as above described they can be quickly assembled and positioned and the same bolts which serve to hold the strips 42 to the springs 38 also serve to secure the units to the casing 10.

To remove the shoe 18 from the casing 10 it is merely necessary to remove the single screw 30 after which the entire shoe can be slid from the casing to permit access to the interior thereof. It will be further noted that the casing 10 and shoe 18 provide guiding means for the sash 9 and that they take the place of the usual side rail or stile which is provided on window frames.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A weather-strip device of the character described including a shoe; means for resiliently pressing said shoe into engagement with a relatively movable member; a latch having a cam portion; a bracket connected to said shoe and having a part adapted to be engaged by said cam portion of the latch whereby when the latch is moved into a predetermined position, the cam will retract the shoe and hold it, against the action of said resilient pressing means, from said member; and means carried by said member for moving said latch into and out of said predetermined position when said member is moved in opposite directions; substantially as described.

2. A weather-strip device including a casing; a resiliently pressed shoe mounted within the casing and adapted to press against a relatively movable member; a bracket on said shoe; a latch having a cam portion for engagement with a part of said bracket, whereby when the latch is moved in one direction the cam will engage said part of the bracket and move and hold the shoe out of engagement with said member against the resilient action of said shoe and when moved in an opposite direction will permit said shoe to engage said member;

and means on said member adapted to move said latch in both of said directions; substantially as described.

3. A weather-strip device including a casing; a resiliently pressed shoe mounted within the casing and adapted to press against a relatively movable member; a bracket on said shoe; a latch having a cam portion for engagement with a part of said bracket, said latch including two arms; and means normally disposed between said arms and operative when said member is moved in opposite directions to move said latch in opposite directions due to alternate contact with said arms whereby when the latch is moved in one direction it will retract and hold said shoe against its resilient action from the member and when the latch is moved in the opposite direction will permit said shoe to engage said member; substantially as described.

4. A weather-strip device including a casing; a resiliently pressed shoe mounted within the casing and adapted to press against a relatively movable member; a bracket on said shoe having a portion projecting outside of said casing, said casing having holes therein; a screw extending through said holes in the casing and through a slot in said projecting portion of the bracket; a latch pivotally mounted on said screw outside of the casing, said latch having a cam portion for engagement with a part of said bracket, said cam portion being adapted, when the latch is swung in one direction, to move said bracket and consequently the shoe, against its resilient action, out of engagement with said member, said cam, when the latch is moved in an opposite direction, permitting said shoe to press upon said member; and means movable by said

member for moving said latch in both of said directions; substantially as described.

5. A weather-strip device of the character described including a casing; a shoe slidably connected to said casing; and resilient means interposed between said casing and shoe; said means including a bowed spring and coiled springs at opposite sides of the center of said bowed spring, said bowed spring having portions for retaining said coiled springs in position; substantially as described.

6. A weather-strip device of the character described including a casing; a shoe slidably connected to said casing; and resilient means interposed between said casing and said shoe, said means including a bowed spring, a strip and coiled springs interposed between the respective end portions of said strip and said bowed spring, said bowed spring having portions for retaining said coiled springs in position; substantially as described.

7. A weather-strip device of the character described including a casing; a shoe slidably connected to said casing; resilient means interposed between said casing and said shoe, said means including a bowed spring, a strip, and coiled springs interposed between the respective end portions of said strip and said bowed spring; and a bolt connecting said strip and bowed spring to the casing; substantially as described.

In testimony whereof I have signed my name to this specification in the presence of two subscribing witnesses.
